Attorney.

UNITED STATES PATENT OFFICE.

WILLIAM EDWARD WALMSLEY, OF LIVERPOOL, ENGLAND.

COLLAPSIBLE BOX.

1,414,236.

Specification of Letters Patent. Patented Apr. 25, 1922.

Application filed February 25, 1921. Serial No. 447,727.

To all whom it may concern:

Be it known that I, WILLIAM EDWARD WALMSLEY, a subject of the King of Great Britain, residing at Liverpool, in the county 5 of Lancaster, England, have invented certain new and useful Improvements in Collapsible Boxes, of which the following is a specification.

This invention relates to collapsible boxes 10 specially designed for holding all kinds of granular, pulverulent or comminuted substances, though they may be used for holding other substances as well, and the object of the invention is to provide a box of cardboard or like material in which the retention 15 and preservation of such substances is secured in a powder-tight manner without leakage, and without of necessity, using any of the well known means used in cardboard 20 box making for fastening the openable ends, such as wire stitching, stapling, riveting, gluing or the like. The box forms a closed powder-tight packet in which substances may be packed for sale, but the box also provides 25 means whereby it may be used by the consumer for sprinkling or shaking out the contents as and when required.

My improved box is made either from a single blank, of cardboard or other like thin 30 material, or from two or more blanks fastened together so as to form a single blank. The said blank is so shaped, and so scored or creased that its flaps may be folded over upon one another, so as to lock themselves 35 together in the form of a box having recessed or countersunk ends, and which when thus erected will hold powdered substances and granular substances securely without shaking out during transit or storage and without 40 out of necessity, using an adhesive or any of the well known mechanical fastening devices commonly used in box making for sealing the openable ends.

The invention consists in cutting and 45 creasing or scoring the end flaps of the ordinary box known in the trade as skillets, cartons or containers in such a manner that they lock themselves together when folded over in position, and make the packet or box 50 so secure that the ends cannot be pushed in or out without damaging the material of which it is made.

The invention will be understood from the

following description, reference being had to the accompanying drawings, in which:— 55

Figure 1 is a plan view of the blank for the box body;

Figure 2 is a perspective view of a box formed from the blank shown in Figure 1, showing the box set up closed at one end and partly closed at the other, and with a portion cut away at the side; and

Figure 3 is a similar view showing the box set up and completely closed at both ends.

Referring to these drawings, the blank (Figure 1) is of rectangular shape creased transversely at suitable intervals 1, 2, 3, 4 to form sections to adapt it to be folded, and produce the four main outer walls 5, 6, 7, 8 of the box body, and a narrow lap or pasting margin 9 which latter when the box is formed up, is secured by paste or other adhesive material to the adjacent wall 5. The two ends of each of the four sections 5, 6, 7, 8 have flaps made integral therewith and extending from each extremity to form the ends of the box. The back flap 10 at both ends of the back section of the box body is made rather larger than the open end of the box body, on every one of the four sides of it, and it is scored or creased on lines which correspond with the dimensions of the open ends, thus forming four wings 11, and the corners 12, are cut away. 85 This allows the flap so scored or creased (and cut) to be bent at its junction 13 with the body 5 of the blank and be pushed into the open end of the box body to the same depth as these wings, thus forming a recessed or countersunk end, with the outer edges of the wings standing up flush with the extremities of the box sides as shown in Figure 2.

The two side flaps 14 (at both ends of the side sections 6, 8) which are shorter are scored or creased at one place parallel with the hinge or score line 15 at their junction with the body of the blank. These flaps 14 are folded inwards over two of the wings 11 of the first mentioned flaps 10 that stand up flush with the extremities of the box sides and against the countersunk end 10.

The front flap 16 at both ends of the front section 7 of the body portion may have two, three or four wings (two only (17, 18) by preference in small cartons) cut, and

- scored or creased, in a similar manner to those of the back flaps but not quite so deep. This front flap 16 is bent inwards at its hinge or junction 19 with body and is pushed 5 down onto the wings or flanges 11 that have been previously pushed into position, the outer edges of its wings 17, 18 standing up flush with the extremities of the box body, as shown in figure 3.
- 10 When the body of the blank has been set up to form the box body, the back flap 10 at one end is folded inwards and pushed into the end of the box the wings 11 being thereby caused to stand up with their outer edges 15 coincident with the extremities of the box body, thus forming a recessed or countersunk end. The two side flaps 14 at this same end are then folded inwards upon the back flap 10 and over two of its wings or flanges 20 11, thus sealing the end at the place where two of the wings or flanges 11 of the countersunk back flap 10 rest against the sides of the box body. The front flap 16 at this same end is next folded inwards so as to lie 25 upon the flaps 10, 14 that have as aforesaid been previously pressed inwards, and this folding inwards of the said front flap 16 causes it to fold over or against the other two wings or flanges 11 of the back flap. This 30 action seals the end at the place where another wing 11 of the countersunk back flap 10 rests against a side of the box body. The result is a box with a closed end of a double thickness in which the closure of the ends is 35 such as to render them impervious or almost impervious to the escape of comminuted material, and which remain secure without the application of an adhesive or the use of mechanical fasteners. An adhesive or fasteners may however be used if so desired.

The box may now be filled with the material with which the box is to be packed, and when this has been done the other end of the box is closed in a similar manner to 45 what has already been described, the result being a box which will retain fine or comminuted or granular substances without leakage or substantially so.

If desired the side flaps 14 aforesaid may 50 be made just long enough to butt up against one another at their meeting ends when folded inwards, but they should not in any case overlap at their meeting ends.

If it be desired to use the box as a dredger 55 to sprinkle or shake out small quantities of the contents, the box is perforated at one part, which perforations are normally closed by a flap or a piece of paper pasted over them. When therefore it is desired to use

the box as a sprinkler, the flap or piece is 60 torn off or such flap or piece perforated by some pointed instrument so as to form an outlet passage or spout.

I declare that what I claim is:—

1. A collapsible box having a body portion with back, front and sides, a flap extending from both extremities of the said back and so made that when folded inwards it forms a head countersunk into the ends of the body portion having outwardly projecting wings or flanges; flaps extending from both extremities of the sides and made to fold inwards over two of the wings or flanges, and flaps extending from both ends of the front so made as to fold inwards over 75 the other two wings or flanges.

2. A collapsible box having a body portion with back, front and sides; flaps extending from the ends of the back portion and made larger than the open ends of the box body 80 so that the said flaps when folded inwards are countersunk into the ends of the box body with the margins standing up and lying against extremities of the four walls of the body on the inside so as to form 85 flanges, flaps extending from the ends of the body side portions and made so as to fold inwards upon the back flap and over two of its wings or flanges; and flaps extending from the ends of the body front portion and made so as to fold inwards and lie upon the previously folded flaps, and be folded over or against the other two wings or flanges of the back flaps.

3. A collapsible box having a body portion 90 with back, front and sides; a flap extending from each end of the back portion but made larger than the open end of the body on every one of its four edges and creased on lines which correspond with the dimensions 100 of the open end thus forming four wings which allows the flap to bend at its junction with the body and be pushed into the open end to the same depth as these four wings; a flap extending from each end of the body 105 side portions and so creased that they can be folded inwards over two of the wings of the back flap and a flap extending from the front portion of the body and so made with wings as to hold over or against the other 110 two wings of the back flap.

In witness whereof, I have hereunto signed my name this 5th day of February, 1921, in the presence of two subscribing witnesses.

WILLIAM EDWARD WALMSLEY.
